CONTAINER

Harry A. Scott, Van Wert, Ohio, assignor to Hans
A. Eggerss, Van Wert, Ohio

Application June 19, 1939, Serial No. 279,925

3 Claims. (Cl. 220—61)

My invention relates to containers. It has to do, more particularly, with a retaining or clamping ring adapted to be applied to the end of a cylindrical container in order to retain a removable head or closure in position at the end of the container.

This invention is particularly applicable to containers of the general type disclosed in the co-pending application of Hans A. Eggerss, Serial No. 158,768, filed August 12, 1937, although it is not necessarily limited thereto. The container disclosed in said co-pending application embodies a cylindrical body portion having a metal head for closing the end thereof, a retaining and clamping ring being provided for retaining the head in position. This invention specifically relates to the retaining and clamping ring. Although the retaining and clamping ring disclosed in said application has a number of desirable features, the retaining ring constituting this invention has a number of additional advantages.

One of the objects of my invention is to provide a retaining and clamping ring of the type indicated which is of such a nature that it may be readily applied to the container and will securely hold the head in position and may be readily removed in order to permit removal of the head.

Another object of my invention is to provide a retaining and clamping ring of the type indicated which is such a nature that it may be used over and over again since it is so constructed that it will not be injured during its application to the container, during its use on the container, or during its removal from the container.

Another object of my invention is to provide a retaining and clamping ring of the type indicated which is split to facilitate application to the container and removal therefrom, novel means being provided in association with the ends of the ring for contracting it around the container and for locking it in contracted condition.

Another object of my invention is to provide a split retaining and clamping ring of the type indicated which is of such a nature that a separate tool is not required for applying it to and contracting it around the container and which does not have any loose locking parts for locking the ends of the ring together.

Another object of my invention is to provide a split retaining and clamping ring of the type indicated wherein the ring contracting and locking means is so located and of such a nature that there will be no projecting or exposed portions

which will be subject to injury or which will injure a person handling the container.

In its preferred form my invention contemplates the provision, in association with a split ring of the type indicated, of mechanism for contracting the ring around the container and for locking it in contracted condition. This mechanism comprises a lever pivoted to one end of the ring and a link pivoted to the opposite end of the ring. The link is also pivoted to the lever at a point spaced from the point where the lever is pivoted to the end of the ring. When the ring is in expanded condition, the lever and the link project outwardly therefrom. However, when the lever is swung inwardly, the ends of the ring are moved into abutting relationship and the ring is contracted. At this time the lever and link are substantially flush with the ring. The ring is provided with a curved rib or bead and the lever and link are provided with similarly curved portions which embrace the rib. The curved portion on the link overlaps the adjacent ends of the ring and holds them in alignment. Suitable means is also associated with the ring for holding the lever in the position it occupies when the ring is contracted.

The preferred embodiment of my invention is illustrated in the accompanying drawing wherein similar characters of reference designate corresponding parts and wherein:

Figure 1 is a perspective view showing a retaining ring having my invention associated therewith applied to the upper end of the container.

Figure 2 is a perspective view, partly cut away, showing the means which I preferably provide for contracting the ring and locking it in contracted condition.

Figure 3 is a top plan view illustrating the device shown in Figure 2, the operating lever thereof being swung outwardly to cause expansion of the ring.

Figure 4 is a similar view but showing the lever swung inwardly to contract the ring.

Figure 5 is a side elevation of the structure illustrated in Figure 4.

Figure 6 is a view taken substantially along line 6—6 of Figure 5.

Figure 7 is a sectional view taken substantially along line 7—7 of Figure 6.

As previously indicated, my retaining and clamping ring is particularly applicable to a container and head structure of the type illustrated in the co-pending application of Hans A. Eggerss, Serial No. 158,768. As illustrated in Figure 8

1. the container structure comprises a body portion 1 which is preferably of cylindrical form. This body portion is preferably made of fiber board although it may be made of other material.

5 2. A head 2 is applied to the end of the container. This head may be of the structure disclosed in said co-pending application and is made of metal although it may be made of other material.

10 The retaining ring 10 which I provide for retaining the head 2 in position on the body portion 1 is a split retaining and clamping ring. It is adapted to be contracted around the upper end of the container and is provided with a portion adapted to cooperate with the head and a portion adapted to cooperate with the body portion of the container so that the head will be held securely in position. It is also provided with novel means for contracting it around the container and for locking it in contracted condition.

15 20 As illustrated in the drawing, the retaining ring has an inwardly projecting portion 11 on its lower edge which is adapted to extend into an external groove formed by bending the body portion of the container in the manner described in said co-pending application. The upper edge of the retaining ring has a portion 14 formed thereon which is adapted to embrace a corresponding portion of the head 2 in order to retain the head in position. Between these upper and lower portions 14 and 11 is an outwardly curved or convex rib portion 16. This portion 16 cooperated with a bead formed on the head 2 in order to retain it in position. When the split retaining ring 10 is positioned on the container 25 and is contracted, the head will be held securely in position on the container.

In order to contract the ring around the container and to hold it in contracted condition, I preferably provide the structure illustrated in Figures 1 to 7, inclusive. This structure is associated with the ends of the split ring which are adapted to be brought into abutting relationship with each other.

This structure comprises an operating lever 17 which has its inner end pivoted to one end of the split ring 10 as at 18. This lever 17 is pivotally connected at the point 19, spaced from the point 18, to the outer end of a link 20. This link 20 has its inner end pivotally connected at 21 to the opposite end of the split ring 10. It will be noted that the lever 17 is bowed throughout its length to a curvature corresponding substantially to that of the ring 10. The same is true of the link 20. It will also be noted that the lever 17 has a cross-section substantially corresponding to that of the rib 16 of the ring so that it will fit over and embrace the rib when it is swung inwardly. Thus, the lever 17 is substantially U-shaped in cross-section as indicated at 22. However, this U-shaped body portion of the lever terminates at the point 23 close to the pivot point 18 so as not to interfere with the swinging movement of the lever. The link 20 is provided with a similar portion 24 of U cross-section adapted to embrace the rib 16. This portion 24 is so located, as will appear later, that it will overlap and embrace both ends of the ring at the point where they abut each other. The portion 24 terminates at a point 25 so as not to interfere with the relative swinging movements of the lever 17 and link 20.

In order to lock the lever 17 in position when it is swung inwardly, I provide the locking lever 26. This lever 26 is pivoted to the same end of the ring as the lever 17 at the point 27 which is

located from the point 18 a distance slightly greater than the length of the lever 17. This locking lever 26 is bowed throughout its length to the same curvature as the ring 10. It is also of U-shaped cross-section, as indicated at 27a, and is adapted to embrace the lever 17. At its pivot point 27, lever 26 has an eccentric cam portion 27b formed therein. This cam portion will engage a notch 27c in the end of lever 17. When lever 26 is swung inwardly the cam 27b and notch 27c produce a camming action which serves to force lever 17 inwardly against the ring and lock it in position. Lever 26 is also provided with a projection 28 on the inner surface of its lower portion which is adapted to snap into a cooperating opening 29 formed in the lower portion of the lever 17 when the lever 26 is swung into embracing relationship with the lever 17. The lever 26 is also provided on its outer end with a depending lug 30 which will lie adjacent a depending lug 31 on lever 17 when the lever 26 embraces lever 17. These lugs are provided with openings through which a wire seal 32 may be passed in the manner illustrated in Figure 5.

When the retaining ring 10 is applied to the container it will be in expanded condition and the various parts of my device will be in the positions illustrated in Figure 3. After the retaining ring is positioned on the container, the operating lever 17 is swung inwardly. This will cause the link 20 to pull the end of the ring to which it is connected towards the other end of the ring and will cause the inner end of the lever 17 to push the end of the ring to which it is connected towards the end to which the link is connected. The lever 17 will be swung inwardly until it embraces the ring. The portion 24 of the link 20 will also embrace the ring. This portion will extend over the joint between the adjacent ends of the ring. Thus, the portion 24 will serve to align the ends of the ring and keep them in alignment. It will be noted that the pivot point 19 is so located that as the lever 17 swings inwardly to its final position, the pivot point 18 moves inwardly beyond the pivot points 19 and 21. This tends to cause the lever 17 to snap into its final position and exerts a force tending to cause it to stay in such position. When the lever 17 reaches its final position, the lever 26 is swung inwardly until it embraces the lever 17, the cam 27b engages with the notch 27c which locks lever 17 in its final position, and the projection 28 snaps into the opening 29 which will hold the lever 26 in locking position. Then the wire seal 32 may be applied.

This structure has many advantages, some of which have been mentioned above. With this structure the ring can be used over and over again. No tool is required in applying the ring 10 and no loose locking parts, which might be lost, are required. The levers and link are shaped to tightly embrace the ring so that they will be out of the way and will be protected from injury. Having the levers and the link of U-shaped cross-section increases the rigidity thereof. In addition, due to the fact that the lever 17 embraces the curved rib 16 of the rim, the tendency for the lever to bend downwardly, caused by the pivot point 18 being lower than the pivot point 19, will be offset. Also, the U-shaped cross-section portion of the link embraces the ends of the ring and keeps them in alignment.

It will be apparent from the above description that I have provided a device having many advantages. Most of the advantages have been

discussed herein. However, others will be apparent from the drawing and the following claims.

Having thus described my invention, what I claim is:

- 5 1. A split ring adapted to be applied to a container or similar article, said split ring having ends which are adapted to be disposed adjacent each other when in contracted condition, means 10 for contracting and expanding said ring, said means comprising a lever pivoted to one end of said ring, a link pivoted to the other end of said ring and to said lever intermediate its ends, means for locking said lever after it has been 15 moved inwardly into its final position, said means comprising a second lever pivoted to said ring adjacent the free end of said first lever, the pivoted end of said second lever comprising a cam eccentrically rotatable on said pivot, the adjacent free end of said first lever having a projection which in operative position substantially contacts said cam, said projection and said cam cooperating to aid in moving into final locking 20 position said first lever as said second lever is 25 moving into its final position.
2. A split ring adapted to be applied to a container or similar article, said split ring having an outer surface which is substantially U-shape, said ring being adapted to have its ends adjacent 30 each other when in contracted condition, means for contracting and expanding said ring, said means comprising a lever pivoted to one end of said ring, a link pivoted to the other end of said ring and to said lever intermediate its ends, 35 said lever being substantially U-shape in cross-section so that when it is swung inwardly into contact with said ring it will fit around and embrace said ring, said link also being substantially U-shape in cross-section so that when it is 40 swung inwardly into contact with said ring it will fit around and embrace said ring, said link being so disposed that when it has been swung inwardly it will overlap the adjacent ends of said ring and will hold them in alignment with each other, means for locking said lever after it has 45 been moved inwardly into its final position, said means comprising a second lever pivoted to said ring adjacent the free end of said first lever, the pivoted end of said second lever comprising a cam eccentrically rotatable on said pivot, the adjacent free end of said first lever having a projection which in operative position substantially contacts said cam, said projection and said cam cooperating to aid in moving into final locking 50 position said first lever as said second lever is moving into its final position, said second lever being substantially U-shape in cross-section similar to the first lever so that it will embrace said first lever when swung inwardly to lock it in position, and means for locking said second lever in embracing relationship to the first lever, 55 said means comprising interfitting portions formed on adjacent surfaces of the two levers which frictionally engage each other when the second lever is swung into embracing relationship to the first lever.

HARRY A. SCOTT.
